UNITED STATES PATENT OFFICE.

AUGUST H. WUNDERLIN, OF FORT WAYNE, INDIANA.

ILLUMINATED ARTIFICIAL FISH BAIT.

Application filed May 1, 1925. Serial No. 27,144.

This invention relates to improvements in illuminated artificial fish baits, and the object thereof is to provide, in a lure having a contained electric lamp and battery therefor, 5 a convenient means for removably securing the battery and lamp in operative relation with each other within the body of the bait, and for making and breaking the electrical circuit between the battery and the lamp. 10 Another object of the improvement is to provide means permanently connected with the battery for mounting the lamp so that the lighting unit consisting of the battery and lamp may be inserted and removed as an 15 assemblage from the body of the bait.

These objects are accomplished by the construction illustrated in the accompanying drawings, in which:—

Fig. 1 is a side view of a fish bait embodying the invention, a portion thereof being broken away;

Fig. 2 is a rear end view of the head portion of the bait;

Fig. 3 is a plan view of the head portion;

Fig. 4 is a front end view of the body portion of the bait;

Fig. 5 is a plan view of the cradle for supporting the lighting unit; and

Fig. 6 is a fragmentary side view of the electric battery including the lamp socket in connection therewith.

The characters appearing in the description refer to parts shown in the drawings and designated thereon by corresponding characters.

The invention comprises a hollow metallic float consisting of a head portion 1 and body portion 2 telescopically connected together, there being T-shaped channels 3 made in the neck 4 of the head portion, and corresponding internal projections 5 in the body portion near the front end thereof, by means of which the head and body portions are fastened together when the neck of the head portion is inserted and turned in the body portion. The head portion 1 has an external shoulder 6 against which the front end of the body portion abuts and an annular rubber gasket 7 imbedded in the neck bears 40 against the interior wall of the body portion 2 and seals the joint between the body portion and the neck. The head portion also has at each side thereof a glass closed aperture 8 simulating an eye through which is emitted light.

Positioned in the body portion is a cradle

9 formed of a metallic plate having lateral upturned brackets 10, the upper ends of which bear against the corresponding sides of the body portion and are secured thereto 60 by means of eye-bolts 11 that extend outwardly through the body and form mounts for the side hooks 12 respectively, there being on each eye-bolt a threaded nut 13 and packing washer 14 for holding the bolt securely in place with a tight joint between the bolt and the body. The cradle has at each side thereof a pair of upwardly curved fingers 15, those of one pair being located slightly in advance of the other pair, and at 70 the rear end of the cradle is a spring 16 formed of an extension of the plate of which the cradle is made. Also, at the front end of the cradle is an upturned lip 16'. The body has at its rear end an eyebolt 17 with 75 which is connected a tail-hook 18, and the head portion has at its front a fastening 19 for the attachment of a fish line.

A feature of the invention is the provision in connection with a battery 20 of a socket 80 21 for the support of a miniature electric lamp 22. The socket is internally threaded to receive the stem 23 of the lamp and is permanently secured in the front end of the battery 20 in axial alinement therewith, the 85 end terminal 24 of the battery projecting into the socket so as to have contact with the end terminal 25 of the lamp. The socket is made of insulating material, preferably of pliable rubber, and is provided 90 with an external annular contact member 26, preferably composed of a coil of wire wound about the socket with one of its ends 27 projecting through the wall of the socket so as to have contact with the stem 95 23 of the lamp when the lamp is mounted in the socket. The battery is positioned in the cradle between the fingers 15 and with its rear end bearing against the spring 16, and its front end being engaged by the up- 100 turned lip 16'. While the battery is thus secured in the body portion, the socket projects within the neck of the head portion, and the contact member 26 becomes engaged by an internal projection 28 in the neck portion when the head portion is turned into locked position for use. In this manner the electrical circuit between the lamp and battery is completed so that the lamp is lighted, the wall of the float and the cradle serving 105 as a conductor that forms the connection between the shell of the battery and the

contact member 26 on the socket while the end terminals of the battery and lamp have direct contact.

In utilizing the invention, the lamp is 5 screwed into the socket and the battery is positioned in the cradle, and the head is connected in the front end of the body, the projections 5 being slid into the T-slots as the body is slid onto the neck of the head.

10 As the head is then turned relative to the body in either direction the head and body are locked together. When the head is turned to one of its locked positions the projection 28 bears against the contact member 15 26 on the socket and the lamp is thus lighted. When the head is turned to its opposite locked position the projection 28 is moved out of contact with the member 26 so that the lamp is extinguished. By securing the 20 lamp, socket and battery together as an assemblage, the lighting unit may be inserted or removed and replaced conveniently without the necessity of making the usual switch and battery wire connections.

25 What I claim is:—

1. In an artificial fish bait, a hollow hook supporting float having two relatively movable portions secured together and having glass closed apertures; a cradle fixed in one 30 of said portions; and electric battery removably secured in said cradle; a lamp socket in supported relation with said battery at one end thereof and extending into the other of said portions; a lamp mounted 35 in said socket, the end terminal of said lamp having direct contact with the end

terminal of said battery; a contact member on said socket having electrical connection with the stem of said lamp; and means operable by movement of one of said portions 40 relative to the other, having engagement with said contact member for completing the electrical circuit between the battery and lamp.

2. In an artificial fish bait, a hollow hook 45 supporting float having separable portions connected together and being relatively movable, said float having glass closed apertures; an electric lighting unit supported in one of said portions; and consisting of an electric battery, a lamp socket in supported relation with the battery and a lamp mounted in said socket; a contact member in connection with said socket; and means in connection with the other of said portions engageable with said contact member and operable to complete the circuit of the lighting unit accordingly as one of said portions is turned relative to the other. 55

3. In an illuminated fish bait, a hollow 60 hook supporting float having separable portions connected together; an electric lighting unit supported bodily in one of said portions; and means in connection with the other of said portions controlling the electric circuit of said unit and being operable by movement of one of said portions relative to the other. 65

In testimony whereof I affix my signature.

AUGUST H. WUNDERLIN.
